United States Patent Office.

THOMAS SMURFIT, OF DAVISVILLE, MICHIGAN.

Letters Patent No. 98,115, dated December 21, 1869.

IMPROVEMENT IN BRICK-MACHINES.

The Schedule referred to in these Letters Patent and making part of the same.

To all whom it may concern:

Be it known that I, THOMAS SMURFIT, of Davisville, Sanilac county, State of Michigan, have invented a new and useful Improvement in Brick-Machine; and I do hereby declare that the following is a full, clear, and exact description thereof, which will enable others skilled in the art to make and use the same, reference being had to the accompanying drawings, forming part of this specification.

Figure 1 is a detail sectional view of my improved machine, taken through the line $z z$, fig. 2.

Figure 2 is a side view of the same.

Figure 3 is a top view of the same, partly in section, to show the construction.

Similar letters of reference indicate corresponding parts.

My invention has for its object to furnish an improved brick-machine, which shall be strong, durable, simple in construction, and effective in operation, making the bricks rapidly and well; and

It consists in the construction and combination of the various parts of the machine, as hereinafter more fully described.

A is the case of the machine, which is made with a double bottom, $a^1 a^2$, the opposite sides of the upper bottom a^2 being cut away, as shown in figs. 1 and 3, to allow the prepared clay to pass down to the press.

B is a vertical shaft that passes down through the centre of the case A, and revolves in bearings in the upper bottom a^2 , and in a cross-bar a^3 , at the top of the case A.

The upper end of the shaft B, that projects above the bar or beam a^3 , is squared off to enter a square socket formed in or attached to the inner end of the sweep C, to the outer end of which the horse is attached.

To the lower end of the shaft B, in the space between the two bottoms $a^1 a^2$, is attached, or upon it is formed, a crank, D, to the crank-pin of which is pivoted one end of the connecting-rod E, the other end of which is attached to the sliding press F, so that if the shaft B is revolved the press F may be moved alternately toward the opposite sides of the press, and force the clay into the moulds alternately.

G are slides placed directly beneath the upper bottom a^2 , so that they may be pushed out to close more or less the openings through which the clay passes to the press, to regulate the feed of the machine.

To the slides G are pivoted the outer ends of the connecting-bars H, the inner ends of which are pivoted to the lever I, upon opposite sides of and equally distant from the shaft B.

The lever I has a hole formed through it, for the passage of the shaft B, so that the said shaft may serve as a fulcrum for the said lever.

The outer end of the lever I extends out through

a slot in the side of the case A, so that it may be conveniently reached and operated by the attendant.

J are arms or wings attached to the shaft B, which, as the said shaft is revolved, sweep through the clay in the machine, keep it thoroughly mixed, and at the same time feed it down to the press.

K are racks placed in the discharge-openings in the opposite sides of the case A, the openings through which are made of the same shape and size as the brick-machine.

The racks K are designed to divide up the clay as it is forced out of the machine, into several streams, and guide the said streams into the moulds.

The inner edges of the cross-bars of the racks K are bevelled off upon both sides, as shown in fig. 3, so that they may offer the least possible obstruction to the egress of the clay.

L are the separators, which move up and down in ways attached to the sides of the case A, and in the lower parts of which are formed openings similar in form and size to the opening through the racks K, so that when the said separators are lowered the openings in the separators may correspond with the openings of the racks K, and form continuations of the guide-spouts, through which the clay passes from the press to the moulds.

When the moulds are full, the separators are raised, and their bottom bar cuts off the streams of clay, or separates the clay in the moulds from that in the machine, leaving the surface of the moulded bricks smooth and ready to be removed from the moulds.

M are levers, pivoted to the sides of the case A, the lower ends of which are connected with the middle part of the upper cross-bar of the separators L by a rope or chain, N, which passes over a guide-pulley, O, pivoted to the side of the case A, so that the separators may be raised vertically by separating the levers M.

The upper ends of the levers M extend above the top of the case A, into such a position that they may be struck and operated at the proper time by the sweep C, or by an inclined block or cam attached to said sweep.

P are the moulds, which are placed upon their edges, with their mouths or open sides opposite the openings through which the clay is pressed out.

The lower parts of the moulds P are supported against outward pressure by a bar, Q, or the side of a groove in which the said lower edge rests.

The upper part of the mould is supported against outward pressure by a bar, R, the ends of which are bent inward, and are pivoted to ears attached to or connected with the case A, so that the said bar R may be turned down to support the mould, or turned up to release it, as desired.

To the middle part of the bar R is pivoted the lower

end of the rod S, which passes up through an eye attached to the outer side of the middle part of the upper cross-bar of the separator L, as shown in figs. 1 and 2.

The upper end of the rod S has a head or other stop formed upon it, and extends above the said cross-bar to such a distance that when the separator has been raised far enough to separate the streams of clay, the eye upon the said cross-bar may strike the stop upon the rod S, and carry the said rod with it, raising the bar R away from the mould P.

The bottom of the groove in which the lower edge of the mould P rests is made to slightly incline outward, so that when released from the bar R, the mould may tip outward and drop upon a platform, barrow, or other device prepared to receive it.

By the alternate action of the press, ample time is given for replacing a full mould with an empty one upon one side of the machine while the mould upon the other side is being filled; and so on alternately.

Having thus described my invention, What I claim as new, and desire to secure by Letters Patent, is—

1. The combination of the bar R and rods S with the separator L, cord N, pulley O, lever M, and sweep C, all constructed and arranged to operate as shown and described.

2. The separator L, rope or chain N, pulley O, and lever M, with the press F, rack K, case A, and sweep C, substantially as herein shown and described, for the purpose set forth.

3. The oscillating lever I, connected with the slides G by links H, and having the shaft B as its fulcrum, when extended laterally through a slot in the side of the case A, to allow the supply of clay to the moulds to be regulated at the will of the operator, as set forth.

THOMAS SMURFIT,
